UNITED STATES PATENT OFFICE.

GEORGE A. DERFLER, OF RIVERSIDE, NEW JERSEY, ASSIGNOR TO PHILADELPHIA WATCH CASE COMPANY, OF RIVERSIDE, NEW JERSEY, A CORPORATION OF NEW JERSEY.

METHOD OF FORMING WATCHCASE-PENDANTS.

No. 866,194.

Specification of Letters Patent.

Patented Sept. 17, 1907.

Application filed April 27, 1906. Serial No. 314,013.

To all whom it may concern:

Be it known that I, GEORGE A. DERFLER, a citizen of the United States, and a resident of Riverside, in the county of Burlington and State of New Jersey, have 5 made and invented certain new and useful Improvements in Methods of Forming Watchcase-Pendants, of which the following is a specification.

My invention relates to an improved method of forming watch case pendants, and more particularly to that 10 kind or style thereof usually known and referred to as "antique", characterized by an oval-shaped enlargement in the center thereof, adapted to receive and contain the ends of the bow.

The object of the invention is to devise a method to 15 simplify and cheapen the construction, and particularly those "antique" pendants wherein the outer side or surface thereof is covered with gold or precious metal, and which have heretofore usually been constructed of what is known as "filled" gold; also, to devise a 20 method wherein the resulting pendant will be of such construction or formation that it will practically be solid, and particularly in the ends of the oval-shaped enlargement, wherein the ends of the bow are contained. Usually these pendants are constructed of sheet metal, 25 the ends of the oval-shaped enlargement being recessed or indented to receive the ends of the bow, which recesses in the course of time, wear through, thereafter allowing said bow to swing and move loosely therein.

With these and other ends in view, the invention 30 consists in the novel method hereinafter described and pointed out in the claims.

In the accompanying drawings, Figure 1 illustrates a blank in the form of a shell, adapted to form the outer covering for the pendant. Fig. 2 is a plug or rod of base 35 metal, and employed to form the interior or body of said pendant. Fig. 3 shows the metal rod inserted in the shell. Fig. 4 shows in elevation, the rod and shell stamped up into a form approximating that of the pendant. Fig. 5 is a sectional view of the same. Fig. 6 is a 40 view of the pendant in its next stage of formation, and Fig. 7 a sectional view thereof. Fig. 8 shows the finished pendant.

Referring to the drawings, A represents the shell, 45 preferably formed of gold or other precious metal, forming in the finished pendant, the outer covering for the base metal body of the pendant. While I prefer to form this shell of thin gold, it will of course be understood that it may be formed from "filled" gold, that is, a metal comprising two outer thin sheets of gold with 50 base metal between them.

To form the body or interior portion of the pendant, I employ the rod B, preferably of brass or other base metal, which will nicely flow under the action of forming dies, this rod being of such a diameter as to nicely

fit within the shell A, as illustrated in Fig. 3, and of 55 somewhat greater length, in order to form the hub C of the finished pendant, and over which hub fits the crown (not shown), said hub being uncovered or unprotected by precious metal, as the same in this type or character of pendant, is entirely concealed within the 60 crown.

After the shell A and rod B have been assembled, as above described, they are subjected to the action of a pair of suitable dies, not shown, whereby they are shaped, as illustrated in Fig. 4, that is, approximating 65 the shape or form of a pendant, the hub B¹ corresponding to the projecting end of the rod B of Fig. 3, the remaining portion of the article being covered by the shell A¹. By means of suitable tools, a portion of the rod B is then drilled out, leaving an interior body or 70 shell D, (Fig. 7), provided with solid oval portions D¹ and hub C, and at the same time, or subsequently, a groove or recess D² is cut into the base metal portions D¹ for the reception of the winding crown, which as in ordinary cases, fits around the hub C. 75

The shell A¹ which covers the body D of the pendant; with the exception of the hub C, at any desired stage of its formation is provided with the indentations or recesses D³, for the reception of the ends of the bows, and as this portion of the shell is backed by the base metal 80 D¹, said ends of the bow are constantly provided with a solid bearing, even through the outer precious metal covering in time be worn through.

The end of the pendant, which is usually soldered or otherwise secured to the watch case center, is knurled 85 or otherwise ornamented with the grooves D⁴ to impart thereto a neat and finished appearance.

This method of forming a pendant is a comparatively cheap and inexpensive one, as it involves but little labor. Furthermore, the outer covering of precious 90 metal is extended over those portions only of the pendant which are exposed to view, and as the shell may be made exceedingly thin, backed, as it is by a base metal body, a material saving in the cost of the finished pendant, is thereby effected. 95

Having fully described my invention, what I claim as new and desire to secure by Letters Patent, is:—

The method hereinbefore described of forming "antique" watch case pendants, consisting in first forming a shell of precious metal and inserting a rod of base metal and 100 greater length therein, then subjecting the same to the action of a die to approximate the form of the finished pendant.

Signed at Riverside, in the county of Burlington, and State of New Jersey, this 20th day of April A. D. 1906.

GEORGE A. DERFLER.
